UNITED STATES PATENT OFFICE.

CHARLES R. A. LONG, OF INDIANAPOLIS, INDIANA.

WINDOW-VENTILATOR.

1,300,850.

Specification of Letters Patent. Patented Apr. 15, 1919.

Application filed December 17, 1917. Serial No. 207,498.

To all whom it may concern:

Be it known that I, CHARLES R. A. LONG, a citizen of the United States, residing at Indianapolis, Marion county, and State of Indiana, have invented and discovered certain new and useful Improvements in Window-Ventilators, of which the following is a specification.

My invention relates to window ventilators, and its objects are to provide means to enable the ventilator to be applied to windows of different widths within a certain range; to provide means whereby the ventilator may be securely mounted in position without the use of screws, bolts or other means of attachment, and whereby the window itself aids in holding the ventilator tightly in position; to provide a construction whereby the admission of air is prevented except through the ventilating openings and whereby in the use of the ventilator it is not necessary to leave a space between the upper rail of the lower sash and the lower rail of the upper sash with the consequent admission of an undesirable current of air; to provide means whereby the rain and snow are effectually prevented from entering the room through the ventilator; to provide means whereby the ventilator openings may be closed or partially closed when desired, and to provide a construction whereby the light space of the window will not be substantially interrupted while at the same time sufficient ventilation is afforded, particularly during the fall, spring and winter months.

With these objects in view, my invention is embodied in preferable form in the construction and arrangement hereinafter described and illustrated in the accompanying drawings.

In these drawings, Figure 1 is an interior front view in elevation of the lower part of a window showing the improved ventilator applied thereto; Fig. 2, a vertical section at right angles to Fig. 1 through the window and ventilator; Fig. 3, a detail enlarged plan view of the ventilator separated from the window; Fig. 4, an end view of the ventilator and Fig. 5, a sectional view on the line 5—5 of Fig. 3, and Fig. 6 an exterior rear view in elevation of the ventilator.

Referring to the drawings, 1 indicates a facing plate of sheet metal which is adapted to lie in a vertical plane and the lower edge

of which is adapted to rest upon or project above the ledge of the window just outside the sill. This plate is approximately two and one-half inches in height, and it constitutes a spacing member determining the extent of separation of the lower rail of the sash from the sill. This plate is provided with a series of air entrance openings 2, covered by screens 3 through which the air is admitted from the outside to the interior of the ventilator. These admission openings are preferably formed by spaced holes in order that the strength of the plate may be retained. Projecting from the inner face of the facing plate and covering the openings 2 therein, is a metallic block or shell 3' consisting of a single piece of metal bent into substantially U-shape form with the inner longitudinal edges of said block bearing against the surface of the face plate and spaced from the upper and lower borders thereof, so as to form with the latter a chamber for admitting and deflecting the air and catching and deflecting the rain and snow.

This block is secured to the facing plate by being nailed or screwed to three plugs or blocks of wood 4 which in turn are secured to the face plate by means of screws 5. The two end plugs constitute closure members for the ends of the block or shell. The upper surfaces of these plugs are slightly spaced from the inner surface of the top wall of the block to provide a slight recess or channel in which is slidably mounted a regulating cut off gate or lid 6 consisting of a flat bar extending longitudinally of the block and having its ends projecting beyond the same whereby it may be manipulated. The said top wall of the block or shell 3' is provided with a series of air exit openings 7 whereby communication is established between the atmosphere and the interior of the room through said openings and the outside openings 2. The block rests upon the sill and thus supports the ventilator, and the one-half inch border portion of the facing plate below the holes 2 projects down parallel with the sill drop. This border portion is made of the standard width employed for ventilators for all windows and is therefore capable of application to any height of sill drop without causing tilting of the ventilator.

Within the chamber of the block and held therein by engagement with the wooden

plugs is a rain and snow deflector consisting of an inwardly and upwardly inclined plate 8 extending from a line below the lower extremities of the openings 2 toward the rear 5 vertical wall of the block and terminating short of said wall so that any rain or snow which may enter through the openings 2 will be deflected by this plate and will fall either into the space between the outer edge 10 of the plate and the facing plate or between the inner edge of the same and the said inner wall of the block and pass through a slight space between the edge of the lower horizontal wall of the block and the facing plate 15 1 and thence to the outer ledge of the sill.

Mounted upon each end of the facing plate 1 is a longitudinally slidable extension plate 9 which constitutes means whereby the ventilator may be extended or contracted 20 to permit it to be adjusted to windows of different widths and also constitutes frictional retaining means whereby the ventilator is adapted to be gripped or pressed against by the window sash in order not 25 only to lock the ventilator firmly in place but also to serve as a limiting stop for the window sash in order to determine the extent of downward movement of the latter and thus locate the bottom rail of the sash relatively 30 to the ventilator openings when the ventilator is in place. These extension members consist of flat plates of metal, the surfaces of which bear closely against the outside surfaces of the facing plate 1 and which 35 are provided with inwardly turned flanges 10 and 11 at the upper and lower borders thereof respectively, adapted to overlap the plate 1 and to bear against the inner surface of the latter. These flanges are shorter in 40 width than the space between the upper edges of the plate 1 and the upper and lower horizontal walls of the block 4 whereby the extension members may be telescoped upon the facing plate to a point beyond the 45 outer ends of the block, whereby a relatively long extension may be utilized. The upper flange 10 of each extension member is cut away for a short distance from the end of said member at 12, in order to leave at this 50 space merely the thickness of the body of the member in order to permit the entrance thereof into the casing channel between the casing rails and the sash rail.

In the application of the ventilator to a 55 window the extension members having been retracted or extended to fit the window between the outer walls of the sash casings 13 formed by the two fixed jamb rails within which the sash slides, the window is raised 60 and the ventilator placed on the sill with the block resting upon the inner sill and the edge of the facing plate 1 abutting against the vertical edge of the inner member and bearing upon the outer sill or ledge, and 65 with the ends of the facing plate or the

ends of the extension members, if the latter are projecting beyond the facing plate, fitting in the casing channels adjacent the front fixed jamb rails thereof. The cut away portions of the upper flange 10 of the 70 extensions permit the extension members to fit flush against said fixed jamb rails. In this position the lower flange will be inside the jamb rail of the casing and the double edge at the cut off end of the upper flange 75 of the extension adjuster will bear against the edge on such casing jamb rail thus slightly tilting the facing plate so as to provide a wedging action for the sash. The sash is then moved down until the lower 80 rail thereof contacts with the outside surface of the facing plate 1 and is firmly pushed down until it moves to a point beyond the width of the upper flange, whereupon it will frictionally grip the facing 85 plate with a slight wedging action and firmly retain the ventilator in position between the casing and the sash and at the same time limit the further downward movement of the sash so that the bottom surface 90 of the latter will be above the upper borders of the openings 2 in the facing plate. The air will then enter from the outside through the openings 2 and 7 into the interior of the room. 95

Owing to the fact that the support for the ventilating chamber block, which also constitutes the means for retaining the device in position by engagement with the sash, consists merely of a flat plate lying 100 in a vertical plane and the lower border of which extends below the shoulder of the sill while the upper border thereof permits the sash to pass down over a portion of its surface in the frictional engagement thereof 105 with the ventilator, it will be seen that it is possible to provide a ventilator of such a short height relatively to the width of the top rail of the lower sash and the lower rail of the upper sash that when the ventilator is in position and the window fitting thereon, the said adjacent rail members of the upper and lower sashes will still maintain an overlapped position, thus preventing the admission of air between them, 110 which admission in the use of ventilators heretofore employed has been an objection owing to the fact that the current of air thus admitted between these meeting rails will strike upon the head of the occupant 115 of the room. This objection has been found to be a serious defect heretofore in the employment of ventilators during the winter, spring and fall months.

The volume of air admitted through the 125 ventilator may be regulated by either pushing the window sash down with sufficient force to carry the lower rail over part of the openings 2, or by adjusting the cut off lid 6 relatively to the openings 7. 130

Owing to the fact that the central meeting rails of the sash are in constant overlapped position, due to the short height of the face plate above the level of the sill and the overlapping position of the lower sash rail and plate, no air at all is admitted between such central meeting rails, and the only point of admission therefor is through the ventilator itself where the volume of air admitted may be controlled by the regulating means above described applied directly to the ventilator. This positive control of the admission of air past the window has not been heretofore practicable of accomplishment in the use of ventilators.

Should it be desired to entirely cut off the air openings of the ventilator, as during excessively cold weather, the sliding lid member 6 may be moved up so as to close the air exit openings 7.

It will be seen that the ventilator may be easily and quickly applied to any sliding window sash without the use of screws, nails or similar means of attachment.

Having thus described my invention, what I claim is:—

1. A window ventilator adapted to be mounted between the sill and the lower edge of the window sash and having a facing plate lying in a vertical plane and operable to space the sash above the sill, said ventilator having a hollow air receiving and deflecting member on the inside of said facing plate and spaced from the upper and lower borders thereof and provided with apertures to admit air from the atmosphere to the interior of the room, said hollow member being adapted to bear on the sill with the lower border of the plate projecting down parallel with the drop and said facing plate mounted to extend into the sash casings to between the front face of the lower rail of the sash and front beading of the jamb when the former is pushed down whereby the ventilator is maintained in fixed position by the frictional engagement of said rail against the surface of said plate.

2. A window ventilator adapted to fit between the lower end of the sash and sill and provided with a facing and spacing plate lying in a vertical plane, said plate being provided with apertures for the admission of air, a hollow apertured block on the inner face of said plate providing a chamber communicating with the apertures in the latter, and longitudinally slid able members mounted on the ends of said plate and telescoping therewith and having retaining means overlapping the border portions of the inner surfaces only of the plate and of a width to permit of the inward projection of the extension members beyond the ends of the block, said extension members being adapted to fit within the sash casings and be engaged between the front face of the lower

rail of the sash and front beading of the jamb so that the ventilator will be thereby clamped into position.

3. A window ventilator adapted to be mounted between the sill and lower edge of the window and comprising a spacing plate lying in a vertical plane, said plate being provided at each end with a flat extension member adapted to telescope upon the plate, said member having flanges bearing against the inner surface of said plate and having one of said flanges terminating short of the end of the member, said extension members being adapted to project within the sash casings with the end of said cut off flange bearing against the sash casing rail, the said extension members being engaged between the front face of the lower rail of the sash and the front beading of the jamb for frictional engagement as the sash is pushed down whereby said downward movement of the sash is limited and the ventilator clamped in position.

4. A window ventilator adapted to be inserted between the sill and the lower end of the window sash and comprising a facing plate of thin cross section lying in a vertical plane, said plate having means extending into the sash casings for frictional clamping engagement between the front face of the lower rail of the sash, an inner beading of the jamb, said plate being provided with air admitting openings, a hollow apertured supporting block mounted on the inner face of said plate and substantially U-shape in cross section, said block being spaced from the upper and lower borders of the facing plate and plugs closing the ends of said block and constituting means whereby the block and plate may be connected.

5. A window ventilator having a thin facing and spacing plate lying in a vertical plane and provided with apertures for the admission of air, said ventilator being clamped into position by the engagement of the plate between the front face and the lower rail of the sash and the inner beading of the jamb, a hollow block on the inner face of said plate provided with apertures for the exit of air into the room beyond the window and secured on the inner face of said plate, said block providing a hollow chamber for deflecting the air and catching the rain and snow, and a deflecting plate within said chamber upwardly and inwardly inclined from the facing plate and terminating short of the rear wall of said block.

6. In combination with a window including its sash, a ventilator adapted to be interposed between the lower end of the sash and the sill and having a spacing and facing plate lying in a vertical plane outside the sill drop, said plate having the ends thereof adapted to enter the sash guiding casings, said plate being apertured for the admis-

sion of air and having a border portion above said apertures which is engaged between the front face of the lower rail of the window sash and the inner beading of the jamb in the downward movement of the window to frictionally retain the ventilator in place and limit the movement of the window, the approximate height of said plate from the plane of support of the ventilator to the upper borders of the apertures being not greater than the width of the meeting rails along the upper border of the lower sash and the lower border of the upper sash whereby an overlapping relation of the said upper rails will be maintained when the ventilator is in place.

7. A window ventilator having a hollow member projecting inwardly beyond the window and constituting an air receiving and deflecting chamber having with a series 20 of air exit openings in its upper horizontal

wall, a slidable closed bar constituting a regulating member for said apertures mounted in the chamber below said horizontal wall, supports in said member at the ends thereof 25 on which said member is mounted for slideable movement, said member being of less width than said horizontal wall and capable of movement from front to rear of the casing to open or close said apertures, said bar having its ends extending freely beyond the ends 30 of said chamber whereby it may be manipulated to effect said forward and rearward adjustment.

In witness whereof, I have hereunto set 35 my hand and seal at Indianapolis, Indiana, this 12th day of December, A. D. nineteen hundred and seventeen.
